UNITED STATES PATENT OFFICE.

GEORGE F. HUTCHINS AND WILLIAM D. THOMPSON, OF WORCESTER, MASSACHUSETTS, ASSIGNORS TO THE CROMPTON & KNOWLES LOOM WORKS, OF SAME PLACE.

TAKE-UP MECHANISM.

SPECIFICATION forming part of Letters Patent No. 595,104, dated December 7, 1897.

Application filed July 24, 1897. Serial No. 645,789. (No model.)

To all whom it may concern:

Be it known that we, GEORGE F. HUTCHINS and WILLIAM D. THOMPSON, citizens of the United States, residing at Worcester, in 5 the county of Worcester and State of Massachusetts, have invented certain new and useful Improvements in Take-Up Mechanism, of which the following is a specification.

Our invention relates to a take-up mechanism which is to be used more particularly in connection with narrow-wear looms. In this class of looms a series of take-up rolls are mounted on a common take-up shaft and revolve with said shaft to take up or wind the 15 fabric as it is woven, and each take-up roll may be revolved in either direction independently of the take-up shaft in case of a shuttle-thread breaking or for any other reason.

The object of our invention is to make an 20 improved take-up mechanism of the description shown and described in our application for Letters Patent of the United States, filed April 12, 1897, Serial No. 631,741, and to simplify and lessen the cost of the take-up mechanism shown in said application; and our invention consists in certain novel features of construction of our take-up mechanism, as will be hereinafter fully described.

Referring to the drawings, Figure 1 is an 30 edge view of a take-up mechanism embodying our improvements mounted on a shaft. Fig. 2 is a central vertical section of the take-up mechanism shown in Fig. 1. Fig. 3 is a view of the hand-wheel detached looking in 35 the direction of arrow *a*, Fig. 1. Fig. 4 is a section on line *c c*, Fig. 2, looking in the direction of arrow *b*, same figure; and Fig. 5 corresponds to Fig. 4, only the hand-wheel is removed and not shown in section in this 40 figure.

In the accompanying drawings, 1 is a portion of a driven shaft, which may be the take-up shaft of a narrow-wear loom.

2 is a flanged gear secured on the shaft 1 45 by a set-screw 3. The flanged gear 2 has gear-teeth 4 extending around its periphery, and also has the annular flange 2' extending out therefrom, and on said flange 2' is mounted to turn loosely the hand-wheel 5, which 50 has the circular recess 5' to fit onto said an-

nular flange 2' and the eccentric opening 5", within which extends loosely a part of what we term the "combination gear-rim" 6, which has internal gear-teeth 6' thereon to mesh with the external gear-teeth 4 on the flanged gear 2. The number of the teeth 6' is greater than the number of the teeth 4. The gear-rim 6 also has external teeth 6" thereon to mesh with the internal teeth 7' on the inner edge of the pulley or roll 7, loosely mounted 55 on the shaft 1. The number of the teeth 6" is less than the number of teeth 7'.

The combination gear-rim 6 turns freely within the eccentric opening 5" in the hand-wheel 5, and the gear-teeth 6' and 6" on said 60 gear-rim 6 are concentric with the portion of said gear-rim which extends within said opening 5".

The eccentricity of the opening 5" in the hand-wheel 5 is equal to the length of a tooth 70 on the combination gear-rim 6 plus any additional amount for clearance. (See Fig. 4.)

The inner edge of the roll 7 bears against the inner edge of the hand-wheel 5, and a collar 8, secured on the shaft 1 by a set-screw 9, 75 acts to keep the roll 7 in position on the shaft 1 and the hand-wheel 5 on the flange 2' of the collar 8, and also the combination gear-rim 6 in place, as shown in Fig. 2.

The operation of our take-up mechanism 80 will be readily understood by those skilled in the art from the above description, in connection with the drawings, and is as follows: When the shaft 1 revolves in the ordinary operation of the loom, the flanged gear 2, fast 85 thereon, will revolve with it and will carry the roll or pulley 7 and the hand-wheel 5 through the combination gear-rim 6, extending loosely within the eccentric opening 5" in the said hand-wheel 5, as above stated. 90 When it is desired to cause the roll 7 to turn in either direction independently of the shaft 1, said shaft continuing to revolve, the hand-wheel 5 is turned in one direction or the other, according to whether it is necessary to turn 95 the roll 7 forward or back. When the hand-wheel 5 is revolved in either direction, said hand-wheel being loosely mounted on the flange 2' of the gear 2, fast on the shaft 1, as above stated, the eccentric opening 5" in said 100

hand-wheel 5, into which the concentric edge of the gear-rim 6 loosely extends, causes said gear-rim 6 to move, so that the internal teeth 6' thereon will be engaged continually with the teeth 4 on the gear 2 through any movement of the eccentric opening 5" in the hand-wheel 5, and it will be seen that by one revolution of the hand-wheel 5 all the teeth 4 on the gear 2 will have been engaged by the teeth 6' on the gear-rim 6, and if there are one or more teeth 6' than there are teeth 4 the movement of the gear-rim 6 will be advanced beyond its original position by the difference in number of teeth between teeth 4 and teeth 6'. An operation of a similar nature will take place between the teeth 7' on the pulley or roll 7 and the teeth 6" on the gear-rim 6 during the same revolution of the hand-wheel 5, and there being more teeth 7' than there are 6" they will be advanced or moved forward in the same direction around the teeth 6" as the teeth 6' are advanced around the teeth 4, and the movement of the take-up roll or pulley 7 independently of the shaft 1 for one revolution of the hand-wheel 5 and eccentric opening 5" therein will be equal to the combined advancement of the teeth 6' and 7', above referred to. The continued revolution of the hand-wheel 5 will cause the take-up roll 7 to revolve on the shaft 1 as desired.

The advantages of our take-up mechanism will be readily appreciated by those skilled in the art.

35 When any force is applied to rotate the take-up roll 7 on the shaft 1 without the aid of the hand-wheel 5, by reason of the multiplying power of said hand-wheel and by reason of the eccentric opening 5" therein the roll 7 will remain positively in any position

given to it by the hand-wheel 5, so that there will be no backward or forward movement.

It will be understood that the details of construction of our take-up mechanism may be varied somewhat from what is shown and 45 described, if desired.

Having thus described our invention, what we claim as new, and desire to secure by Letters Patent, is—

1. A take-up mechanism for looms, &c., 50 consisting of a flanged gear to be secured on a shaft, a pulley or roll to be loosely mounted on a shaft, and having internal gear-teeth on the edge thereof, a gear-rim extending loosely within said teeth, and having external gear-teeth to mesh therewith, and internal gear-teeth to mesh with the teeth on said flanged gear, and a hand-wheel loosely mounted on said flanged gear, and having an eccentric opening therein to receive the concentric portion 55 of the gear-rim, substantially as shown and described.

2. The combination with a driven shaft, of a flanged gear fast thereon, a pulley or roll loosely mounted on said shaft, and having 65 internal gear-teeth, a gear-rim having external gear-teeth to mesh therewith, and internal gear-teeth to mesh with the teeth on said flanged gear, and a hand-wheel loosely mounted on said flanged gear, and having 70 an eccentric opening therein, into which extends the concentric portion of the gear-rim, and means for holding the several parts in place, substantially as shown and described.

GEORGE F. HUTCHINS.
WILLIAM D. THOMPSON.
